UNITED STATES PATENT OFFICE.

CLARENCE J. HAMILTON, OF PLYMOUTH, MICHIGAN, ASSIGNOR OF ONE-HALF TO CYRUS A. PINCKNEY, OF SAME PLACE.

AIR-GUN.

SPECIFICATION forming part of Letters Patent No. 390,297, dated October 2, 1888.

Application filed April 10, 1888. Serial No. 270,171. (No model.)

To all whom it may concern:

Be it known that I, CLARENCE J. HAMILTON, a citizen of the United States, residing at Plymouth, in the county of Wayne and State of Michigan, have invented certain new and useful Improvements in Air-Guns, of which the following is a specification, reference being had therein to the accompanying drawings.

This invention relates to certain new and useful improvements in spring air-guns; and the invention consists in the improved construction and operation of the barrel, all as more fully hereinafter described.

In the drawings which accompany this specification, Figure 1 is a side elevation of my improved gun. Fig. 2 is a vertical central longitudinal section thereof. Fig. 3 is an enlarged section of a part of the barrel. Fig. 4 is an enlarged section of the breech of the barrel. Figs. 5 and 6 are plans of the under side of the barrel, showing the barrel open and closed; and Fig. 7 is a cross-section on line *x* in Fig. 6.

A is the stock. *B* is the false barrel secured thereto. *C* is the air-chamber. *D* is the air-compressing piston of the air-chamber. *E* is the spring acting on that piston. *F* is the piston-rod. *G* is a link secured to the end of the piston-rod. *H* is the lever for compressing the spring. *I* is the trigger. *J* is a detent of the trigger, and *K* is the locking-arm of the piston-rod engaging therewith, all the parts being substantially of the construction and operation as described and shown in a former application for patent, of myself and Cyrus A. Pinckney, Serial No. 260,288, filed January 10, 1888.

My present improvement consists in the novel construction of the breech-block *L* and the true barrel *M*.

Within the false barrel *B*, which I preferably make of sheet metal, in imitation of a gun-barrel of ordinary type, I secure a suitable filling of wood, *N*, and provide it with the longitudinal bore *O*, and within this bore *O* the true barrel *M* is adapted to slide longitudinally from and toward the breech-block *L* to close and disclose the opening *a* in the breech-block.

An opening, *P*, is cut through the under side of the false barrel, near the breech-block, and this opening communicates with the slot *Q*; and through this slot a convenient finger-piece, *R*, secured to the barrel, projects to permit of its easy movement lengthwise and to lock it in closed position against the seat *b* in the breech-block by giving it a little turn to one side, so as to engage the finger-piece *R* upon the shoulder *c*. The finger-piece *R* is preferably in the form of a set-screw, whereby the sliding friction of the true barrel may be increased or diminished. The opening *P* in the barrel leads into the half-circular loading-chamber *S*, which is sufficiently large to permit the operator to insert a dart into the breech of the barrel or to secure a bullet upon the seat *b*. To hold the bullet from accidental displacement in the operations of loading and shooting, I form this seat *b* of conical shape, as shown in Fig. 4, which permits of wedging the bullet firmly into the seat by a slight pressure of the finger; and a small annular recess, *d*, is formed around the top of the seat to receive the breech of the barrel, which is preferably made slightly tapering to seat into the corresponding shoulder or recess *d*. To insure a perfect seat, the shoulder *c*, upon which the finger-piece *R* is engaged, is made slightly angular.

To prevent the loading-chamber from wearing out by the frequent action of loading, it is preferably provided with a suitable metallic lining, *T*, extending more or less around the chamber. To make the breech more accessible for loading, I preferably incline the true barrel within the false barrel, so as to bring the breech close to the under side, while the discharge end may be kept in the middle of the barrel to preserve the appearance, the sights *U* being properly adjusted to offset this angularity.

This construction of the breech leaves a finished and unbroken appearance of the gun-barrel in close imitation of a fire-arm. The loading-chamber being on the under side prevents moisture from easily getting into it, and it requires a position for loading which increases the safety in handling, which in this

class of guns, designed for the younger generation, is desirable and decreases the chances of accidents.

What I claim as my invention is—

- 5 1. In an air-gun, the combination, with a false barrel, of a true barrel rotarily and loosely fitted in said false barrel and confined entirely within the false barrel and adapted to slide longitudinally therein to and from the breech-block, substantially as and for the purpose specified.
- 15 2. The combination, with the false barrel having the recess P, the slot Q, communicating therewith, cut upon its under side, of the locking-shoulder c at the edge of said slot, the true barrel M, slidingly and rotarily secured within the false barrel, and the finger-piece R on such barrel for engaging the shoulder c, all combined to operate substantially as described.
- 20 3. The combination, with the true barrel M, slidingly and rotarily secured within the false barrel, of the loading-chamber S and the tapering seat b in the false barrel serving as a breech-closure for the true barrel, substantially as described.
- 25 4. The combination of the false barrel B, the true barrel M, slidingly and rotarily secured

within said false barrel, and inclined thereto, and the loading-chamber S, formed in the under side of the false barrel, substantially as 30 described.

5. The combination, with the false barrel, of the true barrel slidingly and rotarily secured therein, the loading-chamber S, the recesses P Q, formed in the under side of the false barrel, the locking-shoulder c at the side of such recesses, the finger-piece R on the true barrel, and the tapering seat b in the breech-block to receive the same, all combined to operate substantially as described. 40

6. The combination, with the barrel M, slidingly and rotarily secured within the false barrel and having its lower end conically chamfered, of the breech-block L, provided with the aperture a, the conical seat b, and the annular recess d, the parts being arranged to operate substantially as described. 45

In testimony whereof I affix my signature, in presence of two witnesses, this 15th day of March, 1888.

CLARENCE J. HAMILTON.
